ATTORNEY

UNITED STATES PATENT OFFICE.

ROGER GIST, OF SAN FRANCISCO, CALIFORNIA, ASSIGNOR OF ONE-HALF TO
BENJAMIN F. BLACKMON, OF SAN FRANCISCO, CALIFORNIA.

CLOTHESLINE-HOLDER.

1,345,324.

Specification of Letters Patent. Patented June 29, 1920.

Application filed December 3, 1918. Serial No. 265,158.

To all whom it may concern:

Be it known that I, ROGER GIST, citizen of the United States, residing at San Francisco, in the county of San Francisco, State 5 of California, have invented a new and useful Clothesline-Holder, of which the following is a specification in such full and clear terms as will enable those skilled in the art to construct and use the same.

10 This invention relates to a clothes line holder of the type in which an endless clothes line is used with the supporting pulley at a distance from the place where the clothes are applied to the line. In this 15 instance there are two pulleys for the support of the clothes line at the place where the clothes are applied to the line.

One object of the invention is to provide 20 means whereby the line may be pulled around so that it will stand in a convenient place for fastening the clothes upon the line, and thereafter swung around so that the window of the porch or the room from 25 which the clothes are fastened to the line, may be closed while the clothes are drying.

Another object of the invention is to provide 30 means whereby one line will be held away from the other line to prevent it from touching the clothes, thereby preventing them from being soiled.

35 Another object of the invention is to provide for the safety of the person hanging up the clothes, the arm swinging around into the room to make it possible to hang up the clothes without leaning out of the window.

Other objects of the invention will appear 40 as the description proceeds.

An embodiment of the invention is shown 45 in the drawings in which the same reference numeral is applied to the same portion throughout, but I am aware that there may be modifications thereof.

Figure 1 is a perspective view of the device 50 as it appears applied to a window frame and in use.

Fig. 2 is a perspective view of the window frame to which the clothes line holder has 55 been applied, showing the window closed and the holder outside the window.

Fig. 3 is a perspective view of the holder, 60 and

Fig. 4 is a sectional view of a portion of

the holder showing the manner of securing the movable plate to the clothes line holding arm.

55

In the drawings, the numeral 1 indicates a window frame or other suitable post of a room or porch to which the plate 2 is suitably secured with fastenings sufficient to withstand the considerable weight to be applied thereto.

The plate has two prongs 3 and 4, the former of which has a latch plate 5 pivoted thereon. Mounted on the plate 2 is a plate 6 which may be turned on a rivet 7 which 65 connects it with the plate 2. The plate 6 has two flanges 8 and 9 by which it is pivotally connected to a channelled bar 10 having a small pulley 11 at one end and a larger pulley 12 at the other end.

70

The arm 10 is so pivoted to the flanges 8 and 9 that when said arm is turned at right angles to the position shown in Fig. 3, that said arm may be turned into the slot between the two prongs 3 and 4, and permanently secured in that position by means of the latch 5. Said latch is then turned down to engage the prong 4 and cable 13 passing around the pulleys 11 and 12 in the bottom of the channelled arm 10 and at a distance 80 from the support of the arm 10; said cable passing around a pulley 14 on a post 15 at a suitable elevation from the ground.

75

In operation, the arm is swung around to the position shown in the dotted lines in Fig. 85 3 thereby bringing the rope or cable closer into the room or porch upon which the clothes line holder is installed. The clothes may then be fastened upon the line, whereupon the arm 10 is turned to the position 90 shown in Fig. 2, whereupon the window may be closed.

Having thus described my invention what I claim as new and desire to secure by Letters Patent of the United States, is as follows, express reservation being made of permissible modifications:

95

1. A clothes line holder comprising a wall plate, two lugs carried thereby, a latch on one of the lugs to engage the other lug, a 100 pivoted flanged plate carried by the wall plate, a channel arm pivoted near its middle to the flanged plate and capable of swinging therewith from a vertical position to a sub-

stantially horizontal position between said lugs and behind said latch.

2. A clothes line holder comprising a wall plate, two lugs carried thereby, a pivoted flanged plate carried by the wall plate, an arm having pulleys at its ends pivotally mounted on the flanged plate and capable

of swinging from a vertical position to a substantially horizontal position between the lugs.

In testimony whereof I have hereunto set my hand this 21st day of November, A. D. 1918.

10

ROGER GIST.
